TOY

Andrew Gould, Seattle, Wash.

Application November 29, 1939, Serial No. 306,745

2 Claims. (Cl. 46—51)

My invention relates to toys and more particularly to toys in the form of birds and the like.

One of the principal objects of my invention is to provide a toy in the form of a representation 5 of a bird which can be whirled about in the air in such a way as to simulate the flight of a real bird in the air.

Another object of my invention is to provide a toy of the above described character which is 10 simple in construction, durable in use, efficient in operation, amusing to children and others, and economical in manufacture.

Other objects and advantages will be apparent 15 from the following description, appended claims and annexed drawing.

Referring to the drawing wherein like reference characters designate like parts throughout the several views:

Figure 1 is a perspective view of my invention. 20 Figure 2 is a top plan view thereof, partly in section.

Figure 3 is a sectional view taken on the line 3—3 of Figure 2.

Figure 4 is a detail sectional view taken on the line 4—4 of Figure 3.

Figure 5 is a diagrammatic view illustrating the operation of my invention.

In practicing my invention, I provide a body 4 constructed of upper and lower connected layers 30 of a suitable material 5, for instance, Cellophane or the like. Said body is of a bird-like configuration in plan to simulate the appearance of a bird and comprises head and body sections 6 and 7 respectively. The body section 6 is fashioned with oppositely disposed wing portions 8 and a rearwardly extending tail portion 9.

The head section is constructed of cork 10 or the like between the layers of material and is provided, in the upper side thereof, with a slot 11 40 receiving therein a comb or top knob member 12, the upper end of which extends above the head section 6 and through the upper layer of material. The rear end of the head section 6 is transversely slotted and receives therethrough the 45 looped section of a substantially U-shaped length of wire 13, the outer end sections of which are curved outwardly to define the outer contour of the wing portions 8 and reinforce the material. The body section is provided with a relatively narrow U-shaped length of wire 14, the free ends 50 of which are fixed within the rear end of the head section 6 while the looped end is disposed outwardly or beyond the free ends of the length of wire 13. Said wire 14 extends rearwardly and

is centrally disposed within the body section 7 to reinforce the latter.

One of the wing portions 8, adjacent the head section 6, has secured thereto the end of a string 16, the opposite end of the latter being connected to the end of a wand or stick 17 which is grasped in the hand of an operator whereby the toy may be whirled about, head foremost, in the atmosphere to simulate the flight of a bird as diagrammatically illustrated in Figure 5 of the drawing. 10

From the foregoing, it will be apparent that I have provided a simple and efficient toy which when whirled head foremost about in the atmosphere simulates the appearance of a bird in flight and which lends to the general amusement of 15 children and others.

It is also obvious that the invention is not confined to the herein described use therefor as it may be utilized for any purpose to which it is adaptable. It is therefore to be distinctly understood that the invention is not limited to the specific construction as illustrated and described, as the same is only illustrative of the principles of operation, which are capable of extended application in advance forms, and that the invention comprehends all construction within the scope of the appended claims.

What is claimed is:

1. A device of the character described, comprising, a body constructed of relatively light diaphanous material and having a bird-like configuration, said body fashioned with head and body sections with the latter formed with wing and tail portions, a U-shaped member extending through said head section and terminating at the tip of said wing portions whereby to reinforce the latter, and means connected to one of said wing portions for actuating said body through the air to simulate the flight of a bird, and a relatively narrow U-shaped member connected to said head section and extending through said tail portion for reinforcing of the latter. 30

2. A toy comprising an aviform body constructed of relatively light material and adapted to simulate the flight of a bird when circumvoluted through the air, said body fashioned with head, body and tail sections, and a reinforcing member disposed in a cephalocercal position in said body section and extending through said head and tail sections for effecting conformation 40 of said body and tail sections with respect to said head section. 45

ANDREW GOULD.
